(57) **CLAIM**

The ornamental design for a load mounting system, as shown and described.

DESCRIPTION

FIG. 1 is a top right rear isometric view of a load mounting system showing the new design;

FIG. 2 is a top left front isometric view thereof;

FIG. 3 is a rear elevational view thereof;

FIG. 4 is a right elevational side view thereof, relative to FIG. 3, with the left elevational side being a mirror image;

FIG. 5 is a front elevational view thereof;

FIG. 6 is a bottom plan view thereof;

FIG. 7 is a top plan view thereof;

FIG. 8 is a top left rear assembly isometric view thereof;

FIG. 9 is a top right rear isometric view thereof in an environmental isometric position; and,

FIG. 10 is a top right rear isometric view thereof in an environmental isometric alternative position.

The broken lines shown in the figures are included for the purpose of showing portions of the load mounting system or the environmental structure that form no part of the claimed design.

1 Claim, 7 Drawing Sheets
